UNITED STATES PATENT OFFICE.

FRANK B. KENNEDY, OF NEW HAVEN, CONNECTICUT, ASSIGNOR TO THE RECORDING REGISTER & FARE BOX COMPANY, OF NEW HAVEN, CONNECTICUT, A CORPORATION OF CONNECTICUT.

REGISTERING FARE-BOX.

1,246,608.

Specification of Letters Patent. Patented Nov. 13, 1917.

Application filed June 19, 1913. Serial No. 774,599.

To all whom it may concern:

Be it known that I, FRANK B. KENNEDY, a citizen of the United States, residing at New Haven, in the county of New Haven 5 and State of Connecticut, have invented certain new and useful Improvements in Registering Fare-Boxes, of which the following is a specification, reference being had therein to the accompanying drawing.

10 This invention relates to registering fare boxes and is in the nature of an improvement upon the fare box shown and described in the application for patent filed by me April 21st, 1913, Serial No. 762,506. In the 15 machine of that application the selective actuating device or pinion for the register was driven by a plurality of reciprocating racks, with any one of which it could be moved into alignment. The last teeth of 20 the several racks were arranged in substantially vertical alignment and constituted a lock to prevent the overthrow of the actuating pinion. The pinion remained in engagement with one of these teeth until it 25 had cleared the lowermost rack. Under normal conditions this mechanism operated in an entirely satisfactory manner but it was possible under abnormal conditions for the racks to begin their return movement 30 before the actuating pinion had cleared the lowermost rack, thereby imparting a rearward movement to the pinion and setting the counters back, thus destroying the accuracy of the count.

35 The object of the present invention is to provide a registering fare box of this type in which all possibility of reverse movement being imparted to the pinion and the registering device is eliminated and in which the 40 pinion will be locked against movement at all times when it is not in operative engagement with one of the racks, thus not only preventing the backward movement of the pinion under any circumstance but also 45 preventing the overthrow of the pinion and the registering device when the machine is being operated at a high speed. It is a further object of the invention to provide an actuating mechanism for a machine of this 50 kind which will be simple and durable, and highly mechanical in its construction. To this end I have so constructed and arranged the operating racks that they will pass the

actuating pinion but once, thus allowing ample time for the pinion to return to its 55 normal or idle position; and further, I have mounted the several racks upon a cylinder, the periphery of which acts as a lock and an overthrow prevented for the pinion. Further, it is an object of the invention to 60 provide a rotary actuating device with a resilient tooth so constructed and arranged that it will actuate the pinion a single space and lock the same against further movement. 65

In the accompanying drawings, Figure 1 is a front elevation of a fare box embodying my invention, with the casing and the front wall of the hopper removed; Fig. 2 is a top, plan view of the same; Fig. 3 is a vertical, 70 sectional view of such a fare box; Fig. 4 is a top, plan view of the actuating racks and their coöperating mechanism; Fig. 5 is a detail view of the resilient tooth constituting one of the racks; Fig. 6 is an elevation 75 showing in detail the cylindrical support for the racks and the actuating pinion; and Fig. 7 is a plan view of the mechanism shown in Fig. 6.

In these drawings I have illustrated one 80 embodiment of my invention and have shown the same as applied to a fare box, the main features of construction of which are similar to those shown and described in the above-mentioned application. The manner of handling the coins and operating the 85 selective actuating device for the register need not be described in detail but it will suffice to state that the mechanism as a whole comprises a frame 1 on which is mounted a 90 coin receptacle comprising a movable member to move the coins out of the receptacle. As here shown, this receptacle comprises a front wall 2 and a rotary inclined disk 3 provided on its face with a series of pockets 95 formed by lugs 4 which coöperate with an outwardly extending fixed flange 5 to move the coins out of the hopper. A suitable wiper 6 is provided to prevent a plurality of coins passing from the hopper at one 100 time. Arranged near the top of the inclined disk is a fixed finger or support 7 carried by a plate 8 extending inwardly from the main frame in front of the disk. This finger is pointed and has its point arranged just above the path of the innermost 105

lug 4. Thus, as the coin is moved upward in the pocket formed by the lugs it will be lifted from the innermost lug and caused to ride over the fixed finger or support 7, 5 remaining, however, in engagement with the outer lug 4. Movable mounted above the support or finger 7 is a differentially movable member, such as a pivoted lever 9, connected with the selective actuating device 10 and arranged to be engaged by the peripheries of the coins as they are moved over the fixed support and thus move the lever, and consequently, the selective actuating device, different distances according to 15 the diameters of the coins. The end of the lever is preferably toothed, as shown at 10, and a spring-pressed pawl 11 is provided to engage the teeth and retain the lever in its adjusted position until the register has 20 been actuated, when the device is automatically released and the lever returned to its lowermost or normal position by a spring 12. In the present machine, as in the machine of the application above-mentioned, 25 the register actuating device comprises a slidable pinion 13. This pinion is here shown as rigidly secured to a shaft 14 which is mounted in suitable bearings 15 and 16 for both sliding and rotary movement and 30 has at its upper end a bevel pinion 17 mounted to rotate with the shaft but held against axial movement. The pinion 17 meshes with a bevel gear 18 mounted on a shaft 19 of the registering device or counter 20. Thus, 35 it will be apparent that the rotation of the pinion 13 different distances will advance the registering device or counter different distances. The actuating pinion 13 is connected with the differentially movable member or lever 9 by means of a yoke 21 engaging a grooved collar secured to the shaft, and connected with the lever. The line of movement of the lever is substantially parallel with the shaft 14 and the yoke connection 40 between the lever and the pinion has sufficient play to compensate for the curvature of the path in which the lever moves about its axis.

The differential movements imparted to 50 the pinion, by the coins of different denominations, move the pinion into positions to be engaged by different operating racks arranged in such relation one to the other that the pinion can be successively moved into 55 operative relation thereto. In order that the pinion may have ample time to return from its highest position to its lowermost or idle position without being again engaged by one of the racks I have so arranged the 60 racks in the present instance that they will pass the pinion but once for each registering operation. To this end I have mounted the racks upon a rotary support and have arranged means for tripping the differential lever and permitting the pinion to return 65

to its idle position after the longest rack has passed the pinion. This longest rack is of a length much less than the circumference of the rotary supporting device and, consequently, an appreciable period of time 70 will lapse before the racks will again approach the pinion. While the character of the racks and their support may be varied I have, in the present instance, shown the several racks, which are indicated at 22, as 75 mounted upon a cylinder 23. In the present device there are three of the racks, to take care of pennies, five cent pieces and ten cent pieces, but obviously any number of racks may be provided to take care of any desired 80 variety of fares. Preferably, the racks are arranged one above the other on the cylinder in accordance with the diameters of the coins which they are to register. This arrangement brings the longest rack, for the 85 ten cent piece, in the lowermost position, the single tooth rack for the penny in middle position and the rack for the five cent piece in the uppermost position. In the present arrangement the longest rack is only about 90 one-fourth the circumference of the cylinder. The periphery of the cylinder is so arranged with relation to the pinion that when the pinion is not in engagement with the teeth of one of the racks two of its teeth 95 will be in engagement with the surface of the cylinder and the pinion will, therefore, be locked against movement in either direction. In order to permit the pinion to rotate when engaged by the teeth the teeth are 100 countersunk or recesses are formed between them of a depth sufficient to receive the teeth of the pinion when the latter rotates. Inasmuch as the rear wall of the last recess in effect constitutes a tooth and moves the 105 pinion it will be noted that the five and ten cent racks contain but four and nine teeth, respectively. The cylinder is of such a length that its lower portion will engage the pinion when the latter is in its idle position and, consequently, the pinion is locked at all times, whether it is in alinement with one of the racks or in its idle position, excepting only when it is in actual engagement 110 with the teeth of one of the racks. In this manner, when the machine is operated to register a coin, the pinion will be moved upward, always in engagement with the cylinder and thus held against rotary movement, until it is in alinement with the selected one of the racks. After the rack has engaged and operated the pinion and passed beyond the same the teeth of the pinion again engage the surface of the cylinder and the pinion is locked against movement while 115 it is in alinement with the rack, during its downward movement and while in its idle position. If a single tooth of ordinary construction were provided for actuating the counter to register a penny the recess in the 120 125 130

rear of the one tooth would act as a second tooth and the pinion would be advanced two spaces instead of one. In order to overcome this difficulty I have provided a special 5 tooth for advancing the pinion a single point. To this end the cylinder is provided in the space between the five and ten cent racks with an opening or slot in which is mounted a resilient tooth adapted to yield 10 to permit the rotary support for the rack to move past the pinion when the latter has been advanced the space of one tooth. In the present construction this tooth is in the form of a plate 24 which is pivotally mounted 15 in the slot and the forward portion of which is adapted to move outward under the tension of the spring 25 until it is substantially flush with the outer ends of the teeth of the other racks. The forward edge 20 of the plate extends at substantially right angles to the periphery thereof so as to engage the pinion after the manner of a tooth of one of the racks and rotate the same. As the pinion rotates, the tooth following the 25 tooth which has been engaged by the single tooth or plate 24 will engage the outer edge of this plate and move the same inward against the tension of the spring, thus shortening the tooth and causing it to clear the 30 end of the tooth on the pinion sooner than it would otherwise do, thus moving the pinion a less distance than if it retained its full length throughout its movement. As the end of the plate clears the tooth on the 35 pinion this tooth will engage the outer edge of the plate with which the following tooth is already in engagement, thus locking the pinion against further rotary movement and preventing overthrow.

40 The differentially movable lever 9 is released by the action of the cylindrical support for the racks after the longest rack has passed the pinion. To this end the pawl 11 is provided with a pin 26 extending 45 through an opening in the plate 27 on which the pawl is pivoted and has secured thereto an inwardly extending bar or finger 28, the inner end of which rests normally upon the end of the cylinder. Mounted 50 upon the end of the cylinder some distance from the cylindrical surface thereof is an inclined projection or cam 29. This cam is circumferentially located just beyond the last tooth of the longest rack and as it passes 55 the finger 27 it will force the same outward against the tension of a spring 30 and thus move the pawl out of engagement with the lever and permit the latter to move downward. As soon as the projection has passed 60 the finger the latter moves inward to return the pawl to a position to again engage the toothed end of the lever. However, the length of the cam is such that it will remain in engagement with the finger for an appreciable time, thus retaining the pawl in its in-

operative position for a period ample to permit the return of the lever to its normal position even though the actuating spring or springs may have become sluggish from use.

The cylindrical support for the rack may 70 be rotated in any suitable manner. In the present instance it is mounted upon a shaft 31 having near its lower end a bevel gear 32 meshing with a similar gear 33 on a shaft 34, the outer end of which is connected with 75 a crank 35. It will be understood, however, that other actuating devices may be substituted for the same or that rotary movement may be imparted to the support for the racks in any desired manner. 80

The operation of the machine will be understood from the foregoing description and it will be apparent that in addition to accomplishing the functions ascribed to the various parts I have produced a machine 85 which is very simple and durable in its construction, positive in its operation and which further is of a highly mechanical construction.

While I have shown and described one 90 embodiment of the invention it will be understood that this has been chosen for the purposes of illustration only and that I do not desire to be limited to the details of construction shown and described, for obvious 95 modifications will occur to a person skilled in the art.

Having thus fully described my invention, what I claim as new and desire to secure by Letters Patent, is:— 100

1. In a coin registering mechanism, a hopper comprising an inclined rotatable disk to lift the coins therefrom, a register, a differential operating mechanism for said register comprising a selective device, a movable member operatively connected with said selective device and arranged to be engaged by the coins, as they are moved by said disk, to impart movement to said selective device, and a plurality of devices rotatable about a common axis and arranged to coöperate respectively with said selective device when it is in different positions to cause said register to be actuated in accordance with the value of each coin. 105

2. In a coin registering mechanism, a hopper comprising an inclined rotatable disk to lift the coins therefrom, a register, a differential operating mechanism for said register comprising a pinion movable into 110 different positions, a movable member operatively connected with said pinion and arranged to be engaged by the coins, as they are moved by said disk, to move said pinion into a position corresponding with the denomination of the coin which is in engagement with said movable member, and a plurality of rotary racks of different lengths arranged to coöperate, respectively, with said pinion when it is in different positions 115 120 125 130

to cause said register to be actuated in accordance with the value of each coin.

3. In a coin registering mechanism, a hopper comprising an inclined rotatable disk 5 to lift the coins therefrom, a register, a differential operating mechanism for said register comprising a rotary cylindrical supporting device, a plurality of racks of different lengths carried by said cylindrical supporting device, and arranged in parallel planes, a pinion operatively connected with said register and movable into the plane of any one of said racks and means actuated by the coins as they are moved by 10 said disk for causing said pinion to be moved into operative relation with a selected one of said racks.

4. In a coin registering mechanism, a hopper comprising an inclined rotatable disk 20 to lift the coins therefrom, a register, a differential operating mechanism for said register comprising a rotary cylindrical supporting device, a plurality of racks of different lengths carried by said cylindrical supporting device and arranged in parallel planes, a pinion operatively connected with 25 said register and movable into the plane of any one of said racks and means controlled by the coins as they are moved by said disk for causing said pinion to be moved into 30 operative relation with a selected one of said racks.

5. In a coin registering mechanism, a coin receptacle comprising a movable member to 35 move coins of different diameters from said receptacle, a register, a pinion operatively connected with said register and capable of bodily movement, a cylinder rotatably mounted adjacent to said pinion and spaced 40 from the axis of said pinion a distance less than the length of the radius thereof, a plurality of racks carried by said cylinder on the surface thereof, the teeth of said racks having recesses between the same, and means 45 controlled by the coins for causing said pinion to move into operative relation with a selected one of said racks.

6. In a coin registering mechanism, a coin receptacle comprising a movable member to 50 move coins from said receptacle, a register, a plurality of rotary racks of different lengths, a pinion operatively connected with said register and capable of axial movement, means actuated by the coins to move said 55 pinion into operative relation with a selected one of said rotary racks, and a cylindrical surface arranged beneath the lowermost of said racks and spaced from the axis of said pinion a distance less than the radius of said 60 pinion, whereby when said pinion is in its lowermost position it will be locked against movement in either direction.

7. In a coin registering mechanism, a coin receptacle comprising a movable member to

move coins from said receptacle, a register, 65 a pinion operatively connected with said register and capable of axial movement, a plurality of rotary racks, each of said racks having a cylindrical portion extending beyond the same and spaced from the axis of said pinion a distance less than the radius of said pinion, whereby when said pinion passes out of engagement with one of said racks, said cylindrical surface will engage between two of its teeth and lock it against 70 movement, and means controlled by said coins to move said pinion into operative relation with one of said racks.

8. In a coin registering mechanism, a coin receptacle comprising a movable member to 80 move coins from said receptacle, a register, a pinion operatively connected with said register, means actuated by said coins for imparting axial movement to said pinion, a rotary support mounted adjacent to said pinion, and a rack carried by said support and comprising a single tooth yieldingly mounted on said support and having a curved portion extending rearwardly from the face thereof.

9. In a coin registering mechanism, a coin receptacle comprising a movable member to move coins from said receptacle, a register, a pinion operatively connected with said register, means actuated by said coins for imparting axial movement to said pinion, a cylindrical support rotatably mounted adjacent to said pinion and having a circumferential slot in the periphery thereof, a segmental plate mounted in said slot and pivotally connected to said support at one end thereof, a spring to hold the other end of said plate beyond the surface of said cylinder, whereby the end of said segmental plate will constitute a tooth to engage one of the 100 teeth of said pinion and the edge of said plate will be engaged by the succeeding tooth of said pinion to move the plate out of engagement with the first-mentioned tooth.

10. In a coin registering mechanism, a coin receptacle comprising a movable member to move coins therefrom, a register, a plurality of rotary racks of different lengths, a pinion operatively connected with said register and capable of axial movement, means controlled by said coin for moving said pinion into operative relation with a selected one of said racks, means for holding said pinion in its adjusted position while it 115 is in engagement with said rack, and means controlled by the rotation of said racks to release said holding device.

11. In a coin registering mechanism, a coin receptacle comprising a movable member to move coins therefrom, a register, a rotary support having a plurality of racks of different lengths, a pinion operatively

connected to said register and capable of axial movement, means controlled by the coins for moving said pinion axially to bring it into operative relation with a selected one of said racks, means for holding said pinion in its adjusted position while it is being actuated by said rack, said means comprising a finger having one end arranged adjacent to said rotary support, and a projection carried by said support and adapted to engage said finger to release said holding means after said rack has passed out of engagement with said pinion.

12. In a coin registering mechanism, a coin receptacle comprising a movable member to move coins therefrom, a register, a rotary support having a plurality of racks of different lengths, a pinion operatively connected to said register and capable of axial movement, means controlled by the coins for moving said pinion axially to bring it into operative relation with a selected one of said racks, means for holding said pinion in adjusted position while it is being actuated by said rack, said means comprising a finger having one end arranged adjacent to said rotary support, and a projection carried by said support and adapted to engage said finger to release said holding means after said rack has passed out of engagement with said pinion, said rotary support having a cylindrical surface arranged in the rear of said racks to engage said pinion and hold the same against rotation during its return movement.

13. In a coin registering mechanism, a register, a pinion operatively connected with said register, and a rotary rack mounted adjacent to said pinion and comprising a resiliently supported tooth arranged to engage one tooth of said pinion to actuate the pinion and having a part arranged to be engaged by another tooth of said pinion to check the movement of said pinion, said resiliently mounted tooth being arranged to yield to permit said rack to continue its movement.

14. In a coin registering mechanism, a register, a pinion operatively connected with said register, and a rotary rack mounted adjacent to said pinion and comprising a yieldable tooth arranged to engage one tooth of said pinion to actuate the same and having a rearwardly extending portion arranged to be engaged by the following tooth of said pinion to check the movement of said pinion and adapted to yield to permit said yieldable tooth to pass the first-mentioned tooth of said pinion.

15. In a coin registering mechanism, a coin receptacle comprising a movable member to move coins from said receptacle, a register, a pinion operatively connected with said register, means actuated by said coins

for imparting axial movement to said pinion, a rotary support mounted adjacent to said pinion, and a rack carried by said support and comprising a tooth yieldingly mounted on said support and having a portion arranged to be engaged by a tooth of said pinion to check the movement of said pinion and to cause said tooth of said support to yield to permit said support to continue its movement.

16. In a coin registering mechanism, a register, a pinion operably connected with said register and capable of axial movement, a plurality of rotary racks, each of said racks having a cylindrical portion projecting beyond the same and spaced from the axis of the pinion a distance less than the radius of said pinion, whereby when said pinion passes out of engagement with one of said racks, said cylindrical surface will engage with two of its teeth and lock it against further rotary movement.

17. In a coin registering mechanism, a coin receptacle comprising a movable member to move coins from said receptacle, a register, coin controlled mechanism to actuate said register, said actuating mechanism comprising a rotary rack, and a pinion adapted to mesh with said rack, said rack having a cylindrical extension projecting beyond the same and arranged to engage the teeth of said pinion when said rack passes out of engagement therewith to lock said pinion against further rotary movement.

18. In a coin registering mechanism, a coin receptacle comprising a movable member to move coins from said receptacle, a register, and coin controlled selective actuating mechanism for said register, said actuating mechanism comprising a rack and a pinion, said rack having a smooth portion projecting beyond the same and arranged to engage teeth of said pinion when said rack passes out of engagement therewith and hold said pinion against further rotary movement.

19. In a coin registering mechanism, a coin receptacle having means to move coins therefrom, a register, coin controlled actuating mechanism for said register comprising a series of rotary racks, a pinion, means to move said pinion into operative relation with a selected one of said racks, a device to retain said pinion in operative relation with said selected rack during the operation of said register, and means controlled by the movement of said rack to move said retaining device into an inoperative position and hold it in such inoperative position for a period sufficient to permit said pinion to return to its normal position.

20. In a coin registering mechanism, a coin receptacle having means to move coins therefrom, a register, a plurality of rotary

racks, a pinion operatively connected with said register and capable of axial movement, a coin controlled lever for moving said pinion into operative relation with a selected one of said racks, a detent arranged to engage said lever to hold said pinion in an adjusted position, a finger connected with said detent, and a cam connected with said rotary racks and arranged to engage said

finger to move said detent into an inoperative position and hold the same in such position for a predetermined period of time.

In testimony whereof, I affix my signature in presence of two witnesses.

FRANK B. KENNEDY.
